UNITED STATES PATENT OFFICE.

RUDOLPH CONRADER, OF ERIE, PENNSYLVANIA.

PUMP-GOVERNOR.

SPECIFICATION forming part of Letters Patent No. 687,449, dated November 26, 1901.

Application filed September 10, 1900. Serial No. 29,490. (No model.)

To all whom it may concern:

Be it known that I, RUDOLPH CONRADER, a citizen of the United States, residing at Erie, in the county of Erie and State of Pennsylvania, have invented certain new and useful Improvements in Pump-Governors; and I do hereby declare the following to be a full, clear, and exact description of the invention, such as will enable others skilled in the art to which it appertains to make and use the same.

This invention relates to governors for pumping-engines; and it consists in certain improvements in the construction thereof, as will be hereinafter fully described, and pointed out in the claims.

The object of the invention is to provide pumping-engines with a governor which will increase or decrease the speed of the engine in accordance with its requirements.

Another object of the invention is to provide an automatic stop device, so that in case of accident to the driving-belt or otherwise the governor-valve will immediately close.

Other objects of the invention relate to details of construction, which will appear in the following specification and claims.

Under application filed January 31, 1900, Serial No. 3,473, I have claimed generally a pump-governor having a centrifugal element and a centripetal element and a means actuated by the pumped fluid for varying the relative strength of one of the elements within the limits of the power exerted by the other element. In that device the centripetal element consists of two springs of different strengths, with apparatus actuated by the pumped fluid for changing the centripetal element so as to bring one or the other of the springs into action, and thus change the power of the centripetal element. In this apparatus the pressure device was ordinarily operated from one extreme of its movement to the other with each change of pressure. This was due to the fact that with the apparatus there shown it was difficult to exert a counter-pressure upon the pressure device that would equalize the force asserted by the pressure device throughout its movement. With the present invention I have arranged an apparatus by means of which the pressure on the pressure device may be equalized at all points in its movements, so that the

force of the centripetal element of the governor may be varied throughout the action of the pressure device. This feature of the invention is applicable, however, not only to a governor having the varying centripetal element within the limits of the power exerted by the centripetal element, but is also applicable to that class of governors in which the governor-valve is directly actuated by the pressure device.

The invention is illustrated in the accompanying drawings, as follows:

Figure 1 shows a front elevation of the governor. Fig. 2 shows a side elevation of the governor. Fig. 3 shows a section on the lines 3-3 in Figs. 1 and 2. Fig. 4 shows the details of the stop device.

A marks the valve-chamber. This has the usual valve-diaphragm *a*. The valve *B* is of the usual balanced type and is provided with a stem *b*. The governor is mounted on a frame *C*. This frame is provided with a box *c* for the drive-shaft *d*, the box *c'* for the carrier *E*, and an arm *c''* for the centripetal lever *G*. The drive-shaft is provided with a drive-pulley *D* and a bevel-gear *d'*. The bevel-gear *d'* meshes the gear *e*. The gear *e* is secured to the carrier *E*. The governor-weights *F* are pivoted on the carrier *E* and are provided with the usual link mechanism. (Shown in dotted lines in Fig. 1.) This link mechanism is connected to a stem *b'*, so arranged that with an outward or centrifugal movement of the weights the stem *b'* is pressed downwardly. The stem *b'* and the stem *B* are connected to a yoke *b*, with which the end *g* of the lever *G* engages. The lever *G* is pivoted at *c''* on the arm of *c''*. The centripetal spring *H* is tensioned against a nut *H'* to the collar *h'*. The collar *h'* rests on the end *g'* of the lever *G*. The spring *H* is coiled around the rod *h*. This rod is threaded through the nut *H'* and is provided with a stop-nut *h''*. The rod *h* passes through the end *g'* of the lever *G* and is provided with a nut *h'''* on its lower end. The nut *h'''* and the collar *h'* so engage the end *g'* as to compel its movement in both directions with the rod *h*. The nut *H'* is screwed into the upper end of the sliding frame *I*. This sliding frame is arranged to move in the guides *c''*. These guides are carried by the arm *c''*.

The frame C is carried by a base-plate C'. Extending from this base-plate is a perforated projection C². The perforation of this projection comes directly under the sliding frame

- 5 I. A cylinder L, having the shoulder l', is placed in the perforation. The cylinder has its upper end screw-threaded, and a cap l² is screwed down against the projection C², thus securing the cylinder in place. In order to 10 prevent the cylinder from turning in the socket, a set-screw l³ is passed through the shoulder l' into the plate C². A piston L' is arranged to operate in this cylinder. An inlet L² is connected with the receiver or receptacle (not shown) for the pumped fluid, so that the piston L' is subjected to the pressure of the pumped fluid. A stem l extends from the piston L' to a cross-head i' at the lower end of the frame I. It will readily be seen 15 that with the upward movement of the piston L', by reason of an excessive pressure in the receiver, the frame I is carried so that the tension on the spring H is reduced. This decreases the force exerted by the centripetal 20 element of the governor, so that the centrifugal weights are carried to their outward position at a lower speed than before the movement of the piston. In this way the speed of the engine is reduced. Where the governor 25 is used on a double engine, so that a complete stoppage of the engine is not objectionable, the nut h² may be so arranged that it will contact the nut H' before the piston L' reaches the limit of its upward movement. When 30 the nut H' strikes the nut h², the rod h is lifted positively with the frame I, so that the governor-valve may in this way be entirely closed and the governor thrown out of action.
- In order to compensate for the force of the 35 spring H and to exert a counter-pressure on the pressure device comprised in the cylinder and piston mechanism, I provide the following mechanism: Levers J are pivoted on the cross-head i' and also on the levers K. It 40 will be seen that with the upward movement of the cross-head i', by reason of a forward movement of the piston L', the levers K are pressed outwardly by the toggle-joint mechanism comprised in the levers J J. It will 45 also be noticed that the arm of the lever J is constantly increased with the upward movement, so as to exert a greater force on the levers K as the piston L' moves to its upper position. Extending outwardly from the levers K are the rods m, which are screw-threaded and arranged to turn in the sockets k in the levers K. These rods are provided 50 with a hand-wheel m², so that the rods can be readily operated. Cross-heads m' are screwed 55 on the rods m. Springs M extend between the cross-heads m' and are tensioned to tend to draw the levers K together. Jam-nuts m³ are provided for locking the cross-heads at their desired positions. The springs M should 60 have sufficient strength to prevent a movement of the piston L' before the minimum receiver-pressure is reached. To do this, it is

necessary for the springs M to have sufficient strength to overcome the force exerted upon the cross-head i' by the piston L' and the spring H. The length of the spring is such that the strength of the spring increases approximately as the arm of the levers J increases. Ordinarily the increase in the strength of the spring as it is extended should 70 increase slightly less than the increase in the length of the arm J, because as the cross-head i' is raised the upward tension on the sliding frame I, by reason of the spring H, is decreased. This difference can be adjusted exactly as desired by increasing the initial tension of the springs M, changing their length, or shifting their position on the levers K. By this means the minimum pressure at which the piston L' moves can be controlled, and the 75 pressure at which the piston L' reaches the extreme upward end of its movement can be adjusted and in this way the speed of the engine can be constantly varied after the minimum pressure is reached up to the time that 80 the maximum pressure is reached, when the engine is brought to its minimum speed, and unless the nut h² is adjusted for a double engine the engine is at all times subjected to the action of the governor, so that even when 85 going at the minimum speed should there be an addition to the load which would tend to reduce it below this speed the governor immediately acts to compensate for this additional load. The pressure device, however, 90 of this invention, as before stated, is adapted to operate upon other classes of governors than that shown, and in the broadest phase 95 of my invention I do not wish to be limited to the relation of the pressure device and the connection mechanism between it and the valve shown. In order to limit the upward movement of the cross-head i' as desired, I 100 have provided the stops c⁵. These are in the form of set-screws and are carried by the guide c⁴. The stops i are arranged on the frame I in the path of the stop c⁵.

The automatic stop device is constructed as follows: A head N is journaled on the drive-shaft d. This head is provided with an opening n, through which the drive-shaft passes, the segmental slots n³, and the socket n², in which the rider-pulley arm is placed. Passing through the slots n³ are set-screws n⁵. These set-screws are secured in the flange-piece N². The flange-piece is provided with a segmental flange n'. A lever O is pivoted on the arm c² at c³. The outer end of the lever is provided with a roller o. This is arranged to rest normally on the flange n'. A weight o' is arranged on the lever O and is sufficient to operate the valve as against the strength of the governor when the lever O is released. A lug o' extends from the lever O over the lever G, so as to engage the lever G 115 and vary the lever G with the lever O when the lever O is moved. An arm n⁴ is secured in the socket n³, and a rider-pulley N' is journaled on the end of this arm. 120

The operation of the stop device is as follows: In the normal position of the rider-pulley the flange n' is beneath the shaft d and the roller o rests upon this flange, thus holding the lever O in its upper position. With an accident to the governor-belt the rider-pulley drops to its lower position and the flange n' is carried by the roller o , thus allowing the lever O to drop. This closes the valve.

10 By providing the head with the slots n^3 the head end can be turned relatively to the flange-piece N^2 , so that the stop device may be adapted to an upright engine or to any in connection with a governor-belt.

15 What I claim as new is—

1. In a pump-governor, the combination of a speed-governor comprising a centrifugal and a centripetal element; a governor-valve; a pressure device actuated by the pumped fluid; a lever mechanism connected with said pressure device; a counter-pressure means connected with said lever mechanism in opposition to the pressure device, said lever mechanism being arranged to operate upon one of the elements of the speed-governor and to present a varying arm to the counter-pressure means and pressure device.

2. In a pump-governor, the combination of a speed-governor comprising a centrifugal and a centripetal element; a governor-valve; a pressure device actuated by the pumped fluid; a lever mechanism connected with said pressure device; a counter-pressure means connected with said lever mechanism in opposition to the pressure device, said lever mechanism being arranged to operate upon one of the elements of the speed-governor and to present a varying arm to the counter-pressure means and pressure device, to compensate for the variation in the counter-pressure on the pressure device through the action of the speed-governor element.

3. In a pump-governor, the combination of a speed-governor comprising a centrifugal and a centripetal element; a governor-valve; a pressure device actuated by the pumped fluid; a lever mechanism connected with said pressure device; a counter-pressure means connected with said lever mechanism in opposition to the pressure device, said lever mechanism being arranged to operate upon the centripetal element of the governor and to present a varying arm to the counter-pressure means and pressure device.

55 4. In a pump-governor, the combination with the governor-valve; of a pressure device actuated by the pumped fluid; a lever, J , and a lever, K , arranged in toggle-joint relation—the lever J , being connected with said pressure device; a counter-pressure means arranged to operate upon said levers; and a connecting mechanism between the pressure device and the governor-valve, said connecting mechanism being arranged to influence the action of the governor-valve with a movement of the pressure device.

5. In a pump-governor, the combination

with the governor-valve; of a pressure device actuated by the pumped fluid; a lever, J , and a lever, K , arranged in toggle-joint relation—the lever, J , being connected with said pressure device; a spring, M , tensioned against the lever, K ; and a connecting mechanism between the pressure device and the governor-valve, said connecting mechanism being arranged to influence the action of the governor-valve with a movement of the pressure device.

6. In a pump-governor, the combination with the governor-valve and the centrifugal and centripetal elements; of a pressure device; a lever mechanism connected with said pressure device; a counter-pressure means connected with said lever mechanism in opposition to the pressure device; said pressure device and counter-pressure means being arranged to operate against each other through said lever mechanism on a relatively varying arm; and a connecting mechanism between said pressure device and one of the elements of the governor for varying the strength of one of the elements of the governor relatively to the other element of said governor, within the limits of the power exerted by the other element.

7. In a pump-governor, the combination with the governor-valve and the centrifugal and centripetal elements; of a pressure device and lever mechanism connected with said pressure device; a counter-pressure means connected with said lever mechanism in opposition to the pressure device; said pressure device and counter-pressure means being arranged to operate against each other through said lever mechanism with a relatively varying arm; and a connecting mechanism between said pressure device and the centripetal element of the governor, said connecting mechanism being arranged to vary the strength of the centripetal element with the movement of said pressure device within the limits of the power exerted by the centrifugal element.

8. In a pump-governor, the combination with the governor-valve and the centrifugal and centripetal elements; of a pressure device and lever mechanism connected with said pressure device; a counter-pressure means connected with said lever mechanism in opposition to the pressure device; a spring connected with said lever mechanism in opposition to the pressure device, said spring and pressure device being arranged to operate upon a varying arm of said lever mechanism; and a connecting mechanism between said pressure device and one of the elements of the governor for varying the strength of one of the elements of the governor relatively to the other element of said governor, within the limits of the power exerted by the other element.

9. In a pump-governor the combination with the governor-valve and the centrifugal and centripetal elements of the governor; a

pressure device arranged to be actuated by the pumped fluid; a lever mechanism comprising levers, J and K, arranged in toggle-joint relation; a counter-pressure means arranged to operate upon said levers; and a connecting mechanism between said pressure device and one of the elements of the governor, said connecting mechanism being arranged to vary the power of one of the elements with a movement of the pressure device within the limits of the power exerted by the other element of the governor.

10. In a pump-governor, the combination with the governor-valve; of the cylinder, L; piston, L', therein; the toggle-joint formed by the levers, J and K connected with the piston; the spring, M, arranged to oppose the outward movement of said toggle-joint; and the connecting mechanism between said piston and the governor-valve, said mechanism being arranged to influence the movement of said valve with a movement of the piston, L'.

11. In a pump-governor, the combination of the governor-valve; the lever, G, arranged to actuate said valve; the centrifugal weights, F, arranged to operate upon said valve; the centripetal spring, H; a sliding frame, I, against which said spring is tensioned; the cross-head, i', on said frame; the cylinder, L, connected with the compressed-fluid supply; the piston, L', in said cylinder-stem, I, connecting said piston with the cross-head i'; the levers, J, connected with said cross-head; the levers, K, connected with the levers, J and pivoted at their opposite end on a part of the governor-frame and spring, M.

12. In a pump-governor, the combination of the governor-valve; the lever, G, arranged to actuate said valve; the centrifugal weights F, arranged to operate upon said valve; the centripetal spring, H; a sliding frame, I, against which said spring is tensioned; the cross-head, i', on said frame; the cylinder, L, connected with the compressed-fluid supply; the piston, L', in said cylinder; stem, l, connecting said piston with the cross-head, i'; the levers, J, connected with said cross-head; the levers, K, connected with the levers, J, and pivoted at their opposite end on a part of the governor-frame, and spring, M; and a means for securing said springs to the lever, K, and means for varying the tension of the springs.

13. In a pump-governor, the combination of a centrifugal element; a centripetal element; a pressure device arranged to be actuated by the pumped fluid and to normally indirectly influence the governor-valve by varying the strength of one of the elements within the limits of power exerted by the other element; a governor-valve arranged to be actuated by the governor; and a connecting means between the pressure device and the governor-valve for directly actuating the governor-valve.

14. In a pump-governor, the combination of the centrifugal element; a spring operat-

ing in opposition to the centrifugal element; a pressure device arranged to normally indirectly influence the governor-valve by varying the strength of said spring; and a mechanism for directly connecting the pressure device with the governor-valve at a predetermined variation of the tension of said spring; and said governor-valve.

15. In a pump-governor, the combination of the centripetal spring, H; the lever, G, for operating the governor-valve; the governor-valve; the rod, h', arranged to be engaged by said lever; the sliding frame, I; a pressure device operating upon said frame, said frame being arranged in contact with the spring, H, but in position to engage the rod, h, at a predetermined movement of the sliding frame.

16. In a pump-governor, the combination of a governor-valve; a lever for closing said valve when released; means for holding said lever normally out of operative position; a rider-pulley; an arm carrying said rider-pulley; a connecting mechanism between said arm and said means, said connecting mechanism being arranged to release said lever upon a movement of the arm incident to a movement of the rider-pulley by the normal path of a belt in contact with which said rider-pulley may be placed; a pressure device arranged on the side of the governor opposite the rider-pulley; and means for conveying the action of the pressure device to the valve.

17. In a pump-governor, the combination of a speed-governor; a drive-pulley for said speed-governor; a governor-valve actuated by said speed-governor; a pressure device actuated by the pumped fluid; means for conveying the action of the pressure device to the valve; a stop mechanism arranged to close the valve when released irrespective of the position of the speed-governor or pressure device; and means for releasing said stop mechanism with a change in condition of a drive-belt.

18. In a pump-governor, the combination of a speed-governor; a drive-pulley for said speed-governor; a governor-valve connected with said speed-governor; a stop mechanism comprising a lever pivoted to the side of the governor opposite the drive-pulley and extending by the stem to the side of the governor on which the drive-pulley is placed; a stop mechanism arranged to release said lever when the governor-belt is disarranged; a pressure device arranged to be actuated by the pumped fluid, said pressure device being at the opposite side of the governor from the driving-pulley; a lever for conveying the action of the pressure device to the valve and means on the stop-lever for acting upon the pressure-device lever for conveying the action of the stop-lever when released to the valve.

19. In a pump-governor, the combination of the governor-valve; the stop-lever, O, for actuating said valve; the flange-piece for

holding said lever normally out of position; a head adjustably secured to said flange-piece; and a rider-pulley connected with said head.

5 20. In a pump-governor, the combination of the governor-valve; the stop-lever, O, for actuating said valve; the flange-piece for holding said lever normally out of position; a head with segmental slots, n^5 ; set-screws,

n^5 , arranged to pass through said slots into 10 said flange-piece; and a rider-pulley connected to said head.

In testimony whereof I affix my signature in presence of two witnesses.

RUDOLPH CONRADER.
